UNITED STATES PATENT OFFICE.

TOMLINSON FORT JOHNSON, JR., OF ATLANTA, GEORGIA.

SPARK-GAP INDICATOR.

1,344,042.

Specification of Letters Patent. Patented June 22, 1920.

Application filed August 16, 1919. Serial No. 318,025.

To all whom it may concern:

Be it known that I, TOMLINSON F. JOHNSON, Jr., citizen of the United States, residing at Atlanta, in the county of Fulton 5 and State of Georgia, have invented a new and useful Spark-Gap Indicator, of which the following is a specification.

This invention has reference to spark gap indicators, and its object is to give sensible 10 indication of a breakdown of insulation in high tension alternating current transmission lines.

In the transmission of high tension currents the insulators employed not infrequently 15 break down, sometimes to only a small extent, but if such small degrees of breakdown be allowed to continue a serious breakdown may occur, putting the line entirely out of commission so that customers 20 may be deprived of current for a comparatively long period of time. If a weakening of the insulation be made apparent it may be localized and corrected promptly without in any manner impairing the service. 25 It is possible to discover incipient breakdowns by suitably testing the lines from time to time but this requires the attention of a force of men for doing the testing.

In high tension transmission lines which 30 may carry voltages up to 110,000 volts more or less, it is customary to employ suspension types of insulators in strings each containing a suitable number of insulators in series. There is also another type of insulator 35 capable of withstanding high tension currents, known as the pin-type insulator. In either type of insulator breakdowns, occur which usually are small at first, affecting possibly a single element of the insulator 40 or two or more elements without breaking down the insulator as a whole or all at once, although the incipient breakdown, if neglected, may result in the total destruction of the insulating qualities of the insulator.

45 In accordance with the invention, each insulator is provided with a spark gap, or such spark gap may be multiplied so that every separate element of the insulator is provided with a spark gap. With such an 50 arrangement the spark gap, which is silent under normal conditions, becomes audible, or audible and visible, thereby giving warning that the insulating qualities of the insulator will deteriorate and need prompt attention to prevent interruption of service. Such an indicator is made a permanent part

of the installation, requires no attention and is entirely automatic in its operation. All that is required is occasional inspection, without the necessity of any testing, for 60 simple observation, will show to an inspector whether or not the installation is in proper condition so far as the insulators are concerned.

The invention will be best understood 65 from a consideration of the following detailed description taken in connection with the accompanying drawings forming part of this specification, with the understanding, however, that the invention is not confined 70 to any strict conformity with the showing of the drawings, but may be changed and modified so long as such changes and modifications mark no material departure from the salient features of the invention as expressed in the appended claims.

In the drawings:—

Figure 1 is an elevation of a string of suspension insulators with each unit provided with a spark gap.

Fig. 2 is a similar view showing but one of the units provided with a spark gap.

Fig. 3 is a view partly in elevation and partly in diametric section, of a pin-type insulator provided with a spark gap for 85 each unit.

Fig. 4 is a similar view showing but one of the units of the pin-type insulator provided with a spark gap.

Fig. 5 is a view of an element of a string 90 of suspension insulators provided with a spark gap and drawn on a larger scale than Figs. 1 and 2.

Fig. 6 is a view similar to Fig. 5 but showing another type of spark gap.

Fig. 7 is a plan view of the spark gap element shown in Fig. 6.

Fig. 8 is a view similar to Fig. 6 but showing a somewhat different type of spark gap element and insulator.

Fig. 9 is a detail view on a larger scale than the other views showing an arrangement of the spark gap.

Considering first suspension insulators, there is shown in Figs. 1 and 2 a string A 105 of suspension insulators made up, in the particular showing of the drawings, of eight insulator elements, numbered consecutively from 1 to 8 and extending between a cross beam 9 and a line wire or conductor 10, 110 which latter may be considered as carrying alternating current at 110,000 volts. For

such a voltage eight insulators constitute the proper number between the line wire and the supporting structure, such arrangement having been established by practice.

5 Each insulator comprises a metallic cap 11 and a porcelain part 12, neither of which require any special description or showing, since they may be of standard construction.

Such a string of suspension insulators 10 is, in effect, a string of condensers, the porcelain parts of the insulator being the dielectric and the metallic couplings between the insulators constituting the plates of the condensers. It is not necessary that 15 these couplings be actually metallic so long as they are of conducting or semi-conducting material.

The spark gap structure may comprise a conductor 13 connected to and supported on 20 the cap 11 by a block 14 of insulating material. The conductor 13 at the end remote from the block 14 terminates in a ball or enlargement 15 brought into sufficiently near approach to the insulating or conducting element of the insulator to answer the purposes of the invention. Some types of insulators are provided with grooves between the cap 11 and the porcelain member 12 and such groove may be utilized as a seat 25 for a broken ring 16 of metal with a series of bulbs or blocks 17 of insulating material thereon for holding the ring 16 in place but out of actual contact with the porcelain or conducting element. Extending from the 30 ring 16 is a conductor 18, which may be conveniently made of wire, and terminating in a ball 19 which may be so situated as to be in proper relation to the cap 11. Still other types of insulators are provided with metallic spiders 20, as shown in Fig. 8, taking the place of the cap 11 and carried by the porcelain member 12. Also carried by the porcelain member 12 is a conducting rod or wire 21 terminating in a ball 2 and brought 45 into sparking distance with relation to the spider 20. The several examples given are sufficient to show that the invention is adaptable to a great variety of insulators.

Now, since a string of insulators such as 50 shown in Fig. 1 or Fig. 2 is really a string of condensers in series, the electric charge on the various caps of the insulators decreases from the line wire 10 to the cross arm 9, that is, the cap on the insulator 1 has 55 a certain charge on it, that of the insulator 2 has a less charge and the other caps have progressively smaller charges. However, on any given line with a given number of insulators in a string, the charge on corresponding caps in every string, when all the 60 insulators are good, is always equal. For instance, the charge on the cap of insulator 1, when the insulator is good, is equal to a certain amount. If the insulator 1 becomes 65 defective the charge on the cap thereof will

increase and so will the charges on the caps of insulators 2, 3, 4, etc., as these insulators become defective. If any insulator in a string becomes defective the charge on all the caps in the string will increase due to the effect 70 of the defective insulator. Therefore, if a spark gap be established by using the head of the insulator as one side of the gap and a piece of properly shaped metal as the other side of the gap, this piece of metal being 75 insulated from the head of the insulator, the gap may be set at such a distance that it will be noiseless and will not fire so long as the charge on the head of the insulator to which it is attached is correct. By properly 80 setting the gap an increase in the charge on the head of the insulator will cause it to jump across the gap. When the insulator is but slightly defective the arc across the gap cannot be seen but can be heard. When the 85 insulator becomes more defective the arc across the gap can be both seen and heard.

In Fig. 1 it is assumed that such spark gaps as have been described are established on the cap or head of each insulator with 90 the spark gaps properly set. Any defect in any insulator will be indicated by the spark gap on the head of that insulator firing or becoming noisy. This firing is only a small brush discharge and the arcs, while very 95 noisy, are in nowise detrimental to the insulating qualities of the string.

The showing of Fig. 1 covers the case in which the spark gap is applied to each and every individual insulator constituting a 100 string or stack of insulators in series between the line and the supporting structure, and in case of some one or more of the insulator units becoming defective the particular units are indicated. However, 105 similar results can be obtained by establishing properly adjusted gaps in any number of individual insulators on a string with such number of gaps less than the total number of individual insulators. If one insulator in a string is selected and a spark gap established on this insulator and any individual insulator or unit develops a defect the voltage across the gap is raised, thus causing the string of insulators to become 115 noisy or visibly fire at the spark gap. This would not necessarily indicate that the individual insulator or unit to which the gap was attached was defective but would definitely indicate that some one or more of the 120 units of the string were defective.

In the structure shown in Figs. 3, 4 and 9 there appears a pin type of insulator including a pin 23 on which is mounted a series of insulating units 24 surmounted by 125 a line conductor 10. The units 24 are of the nested petticoat type with each inner unit entering the next larger one and united thereto by a suitable cement 25, which cement may be of semi-conducting type. 130

- Fast, in the form shown in Fig. 3, to each porcelain petticoat beyond the one carrying the line conductor 10, is a block 26 of insulating material carrying a metallic finger 27 terminating close to the cement 25 so as to provide a spark gap, which latter, of course, must be properly set. In the form shown in Fig. 4 the same result is obtained by the use of a single conducting finger 27, 5 the arrangement being otherwise the same as in Fig. 3. Fig. 9 may be considered as representative of either of the forms of Figs. 3 and 4. In either the string of suspension type insulators or the pin type insulators 10 there is a series of insulating units separated from each other and held together by conducting or semi-conducting material. The structures act similarly in so far as the invention is concerned so that what may be 15 stated with respect to one type of insulator applies to the other.
- What is claimed is:—
1. A high tension alternating current transmission line provided with insulators 20 for supporting the line, said insulators having permanent spark gaps each set to remain silent under normal conditions of transmission and to sensibly respond to a lessening of the insulating qualities of the 25 insulators as a whole.
  2. A high tension alternating current transmission line provided with insulators for supporting the line and each comprising a plurality of insulating units, and per- 30 manent spark gaps in the insulators each set to remain silent under normal working conditions and to sensibly respond to a lessening of the insulating qualities of the insulators.
  3. In a high tension alternating current transmission line, an insulator formed of a series of insulating units with intervening portions having electrical conducting qualities, a spark gap structure comprising a me- 35 tallic member carried by an insulator unit and in proximity to and separated from a conducting part of the insulator by a distance too great to admit the passage, in an audible manner, of current at normal volt- 40 age.
  4. A high tension alternating current transmission line provided with insulators for the line, each consisting of a plurality of condenser units, and spark gaps carried by 45 the insulators and adjustable for the bridging of the gaps by the line current when the voltage at the gaps becomes abnormally high, whereby to indicate to an observer that abnormal conditions are present.
  5. A high tension alternating current 50 transmission line having insulators for the line, each insulator comprising a plurality of condenser units, and means on an insulator for sensibly indicating to an observer diminished insulating qualities of the insu- 55 lator.
  6. A high tension alternating current transmission line having insulators supporting it, with each insulator comprising insulating units in series with conducting ma- 60 terial alternating with the units, and conducting means carried by an insulating part of the insulator and approaching but stopping short of a conducting part of the insulator to provide a spark gap re- 65 sistant to bridging by current at normal voltage and responsive to current of a higher voltage, whereby on the development of a defect in the insulator sensible evi- 70 dence of the defect is imparted to an ob- 75 server.
  7. A high tension alternating current transmission line provided with insulators carrying it, each insulator comprising alter- 80 nate insulating and conducting members, the insulators each having conducting means approaching but stopping short of one or more of the conducting members of the insulator to provide a spark gap for a discharge across the spark gap on a rise of 85 voltage above the normal at said spark gap.
  8. A high tension alternating current transmission line provided with insulators carrying it, with each insulator composed of a series of alternately arranged insulating 90 and conducting members and each insulator provided with a conductor carried by an insulating member and stopping short of the next conducting member in order to provide a spark gap adjusted to prevent a discharge 95 across the gap of current at normal voltage at the gap and permit a discharge of current of higher voltage.
  9. A high tension alternating current transmission line provided with insulators carrying it and each consisting of a series 100 of condenser units with each unit provided with a spark gap resistant to the passage of normal current and responsive to the passage of current of higher voltage than nor- 105 mal due to the break-down of any one or more of the condenser units.
- In testimony that I claim the foregoing as my own, I have hereto affixed my signature.
